UNITED STATES PATENT OFFICE.

DAVID ZUG, OF SHAFFERTOWN, PENNSYLVANIA.

IMPROVEMENT IN HARVESTERS.

Specification forming part of Letters Patent No. 35,485, dated June 3, 1862.

To all whom it may concern:

Be it known that I, DAVID ZUG, of Shaefferstown, in the county of Lebanon and State of Pennsylvania, have invented certain new and useful Improvements on Harvesters or Mowing and Reaping Machines; and I do hereby declare that the following is a full, clear, and exact description of the construction and operation of the same, reference being had to the accompanying drawings, making a part of this specification, in which—

Figure 1 is a perspective view of the main parts of the machine with the several improvements in place. Fig. 2 shows the connection of the gearing and shifting lever; Fig. 3, a detached view of the gearing and ungearing lever. Fig. 4 illustrates the sliding screw-boxes for the reel-shaft disconnected. Fig. 5 is an enlarged view of the double flanged and slotted hanger. Fig. 6 illustrates the driving-wheel with its ratchet-box having the pawl-head $6'$, removed. (6 ^{2} shows the inside of the pawl-head.) Fig. 7 illustrates the outer regulating-plate, Q, for the pulley N and its loose perforated lug O. Fig. 8 shows the hooked arrangement for connecting the spring-bar V with the main bar K, removed from each other. Their connection is shown in Fig. 1.

I deem it simply necessary to confine myself to those parts considered as improvements. In the first place, the construction of the slotted two-flanged hanger attached below the rear cross-piece of the truck 5, Fig. 5. The vibrating bar Y is affixed by a pin in the bracket at one end, enters the slot between the flanges 8 8 of the hanger. These flanges and the slot are slightly curved to accommodate the same to the up-and-down motion of the spring-arm V. The flanges also have a series of holes opposite each other for a pin, which confines the bar at any desired point and affords a wide scope for adjustment, besides enabling the driver at short notice to raise the entire sickle-bar from the ground sufficiently high to carry it over stumps and large stones (especially when cutting grass) by means of the ratchet-lever T, with its cord or chain passing over the pulley G and its connection to the arm X K at l. The bar Y, being connected to the main or finger bar K, supports it, together with the inner shoe, Z, sickle-bar H, by means of the hanger, Fig. 5, and obviates the necessity of a supporting pulley under the shoe.

In order to adjust the outer end of the bar K, attached to the dividing-shoe L, and keep it parallel with the ground, I use a hinge-plate, Q, Fig. 7, having projecting knuckles or ears 1, 2, and 3. For the adjustment of the arm n n of the pulley-wheel N, Fig. 1, a pintle of sufficient length enters these ears and pulley-arm. I also employ a loose perforated lug, O, which may be set under or over a pulley-arm on either side of the ears, and thus form an intermediate support, also steadyng the connection of the arm n n on the hinge-plate Q, with its flanges 4 4 5, constituting the second improvement.

My improvement further consists in the peculiar arrangement of the click or pawl-head operating within the ratchet-box b, Fig. 6. These pawl-heads, Fig. 6, 6', have a central tube slipping over the axle w of the machine and entering the bore of the traction-wheels B. The outer end of the pawl-tube is affixed to the axle by a pin and revolves with it, while the traction-wheels move on the entering tubes c of the pawl-heads. The ratchet-box hub b receives the offset e, and the clicks or pawls d d arrest the forward motion of the traction-wheels B, thereby operating the connected gearing c n q, &c. In backing the machine, however, the traction-wheels are not arrested by the pawls, but revolve on the tubes c without giving any or a reverse motion to the gearing. 6 ^{1} is the external and 6 ^{2} the internal face of the pawl-head; f, the covering-flange; d, the clicks or pawls; g, the springs; c, the tube. This arrangement obviates the unseemly fixings of the pawls externally around the hub, looks neater, is more compact, and in every respect superior. The box s, which supports the end of the shaft II and the beveled pinion operating the crank-pulley x x, is supported by and slides upon the boxes y y, (which latter support the axle w of the machine.) The external portion of box s has a raised flange over which the forked end of the shifting-lever u fits, which lever has its fulcrum in the curved arm k. On the top there is a long slot with two recesses on one side, in which the lever is held by a spring operating against the opposite smooth side of the slotted and chambered plate. Thus by drawing it back or forth from one catch into the other the box s is moved, carrying the shaft and pinion with it out or into gear with the wheel q, acting or

arresting the motion of the crank-pulley at pleasure, which latter operates the sickles in the ordinary way by a pitman or connecting rod.

My improvement further consists in the specific construction and arrangement of the sliding boxes $H' H^2$, (shown on the reverse sides,) in the manner they set against the recess cut out of the inner sides of the uprights E, Fig. 1. H^2 shows the inner raised T-flange into which the screw-thread is cut, and the supporting-groove for the reel-shaft I I I, with its pulley I. H' shows the hole for the reception of the inner end of the shaft. The reel attached to the outer end is not shown. F are long screws resting within the wood-work of the uprights, and the broad heads on the top of the cross-piece, Fig. 1. By means of these screws F acting upon the boxes $H' H^2$ through the thread cut into the flange upon which they also slide, the reel-shaft can be adjusted to any desired height demanded by the size of the grain to be cut, also affording great facilities in tightening the operating-cord over the pulleys. I have also modified the position of my gum-elastic stuffing-box P and its connection, for which I obtained Letters Patent bearing date October 4, 1859, being, however, deemed substantially the same. I now place the gum-elastic stuffing-box under the front cross-piece of the truck, and provide the spring-bar v (connected therewith by a bolt to which it is hinged at one end, the other being furnished with a hook, r, to embrace the inner shoe, z, of the main bar K) with a perforated lug, t, over which the open slotted end of the shoe locks, so that instead of turning it over on its hinged connection, the main bar K, with its appendages, is simply unhooked by hand and laid (being detached) across the rear of the truck fitted for its reception, the ratchet-

lever, rope, or chain being detached from the ring l on x to the ring r on the hook, Fig. 8, in order to prevent the spring-bar v and pitman from dragging. The platform, when used, is readily removed, and so formed as to lodge on the side of the truck under the uprights F of the reel, the reel being first also placed into its appropriate place on the truck when going to or from the field, being all compactly secured and readily put on and taken off.

I do not claim the stuffing-box P; nor do I claim the general construction of the truck and traction wheels and sickle-bars or gearing, these being common.

What I claim, and desire to secure by Letters Patent as an improvement in harvesters, is—

1. The tubulated and flanged pawl-heads C^1 , connected with the main shaft or axle W of the machine, in combination with the ratchet-box b, which forms the hub of the traction-wheels B, and is supported on the tubes c of the pawl-heads, for the purpose and in the manner specified.

2. The double flanged and slotted hanger, (5,) constructed and applied in the manner and for the purpose specified.

3. The specific construction and arrangement of the hinge-plate Q, for adjusting the pulley N on the dividing-shoe L, in combination with the loose and changeable perforated lug O, for the purpose set forth.

4. The arrangement and construction of the T-flanged sliding screw-boxes $H' H^2$, in combination with the screws F, for regulating the reel-shaft in the manner specified.

DAVID ZUG.
